UNITED STATES PATENT OFFICE.

GEORGE H. DAWSON, OF CAMBRIDGE, MASSACHUSETTS, ASSIGNOR, BY MESNE ASSIGNMENTS, TO REMINGTON RAND INC., OF TONAWANDA, NEW YORK, A CORPORATION OF DELAWARE.

CARD-INDEX TRAY.

Application filed December 5, 1921. Serial No. 520,184.

This invention relates to a card index tray in which cards are removably supported in overlapping relation, the tray being adapted for insertion in a cabinet.

5 It is an object of this invention to provide a simple and economical tray structure which is readily adjustable whereby a card and its support may be readily inserted and removed and in which one or 10 more cards may be securely locked against endwise movement and in which a series of cards may be held in adjusted position with respect to the others.

With these and other objects in view 15 which will become more apparent in the following description and disclosures in the drawing, my invention comprises the novel structure and mechanism hereinafter described and more particularly pointed out 20 and defined in the appended claims.

In the accompanying drawings which illustrate a preferred embodiment of my invention and in which similar reference numerals refer to similar features in the different views:

Figure 1 is a top plan view of the tray.

Figure 2 is a plan view upon a decreased scale of the tray partially filled with cards entering a tray chamber of a cabinet shown 25 in section.

Figure 3 is a longitudinal sectional view through the tray with parts in elevation and parts omitted upon an enlarged scale.

Figure 4 is a transverse section through the tray showing the locking means that is 30 adapted for holding the cards in compact position upon an enlarged scale.

Figure 5 is a perspective view of an adjustable abutment for the tray upon an enlarged scale.

Figure 6 is a perspective view of the stationary abutment for the tray upon an enlarged scale.

Figure 7 is a section on the line 7—7 of 35 Figure 3.

Figure 8 is a fragmentary section through the guides of the tray showing the card supports in transverse section upon an enlarged scale.

Figure 9 is a fragmentary front view of the tray with a number of overlapping cards supported therein upon an enlarged scale.

Figure 10 is a fragmentary vertical sec-

tion through lower end of the tray upon an 55 enlarged scale.

Figure 11 is a front end elevation of the tray upon an enlarged scale.

Figure 12 is a section on the line 12—12 of Figure 3 upon an enlarged scale. 60

Figure 13 is a section on the line 13—13 of Figure 3 upon an enlarged scale.

The tray or frame that embraces my invention is primarily designed to be used in a cabinet, but it is obvious that it is susceptible of being used in suspended form or secured in a revolving rack. The tray is preferably constructed from an integral sheet of flexible or resilient metal having 65 its lateral margins folded over the front 70 face in preferably angular form for the purpose of providing inwardly directed channel-like chambers 1 and 2 of unequal width in which perforated bars are secured, which bars form the outer walls of the 75 guideways 3 in which the mounted cards are supported. These guideways are formed by the terminal margins or flanges 4 which extend inwardly from the channel-like chambers with their inner ends at a slight inclination to the body of the tray 80 to facilitate the removal and insertion of the mounted cards in the tray.

These flanges 4 extend preferably from the top of the tray to a shelf 5 spaced a 85 suitable distance from the bottom or front end of the tray. The shelf 5 in the present construction is formed upon an inclined plate 18 which is provided with a flange 19 crimped around the lower or forward edge 90 of the body of the tray as shown in Figure 10. This flange 19 forms the front part of the tray and may be provided with a finger grip 20 as shown in Figures 10 and 11. At the rear end of the tray there is a limit or 95 stop member 5^a that confines the card supports.

The bars in the channel-like chambers comprise channels 6 and 8 which have evenly spaced perforations 7 in their webs. The channel bar 6 is located in the left-hand channel-like chamber 1 as viewed in Figure 3 and fits snugly with its perforated web directed inwardly to form an abutting guide wall for the card supporting bars. The channel bar 8 which is provided with an abutment 9 extending transversely to a flange thereof is adjustably mounted in the 100 105

channel-like chamber 2 which is the wider of the two upon a pair of inclined pins or supports 10 extending across the chamber 2 and secured in the walls thereof. The 5 bar 8 is laterally and obliquely adjustable upon its supports from full line position to dotted line position (Figure 3).

In order to adjust the member 8 from full line position to dotted line position as shown 10 in Figure 2, a stud 11 is secured thereto and projects through a diagonal slot 12 which is parallel with the pins 10 and which extends through the top of the channel-like chamber 2. The stud 11 is adapted to be operated 15 by a pair of toggle links 13, pivotally connected together by a pivot pin 14, the outer end of one link being connected to the stud 11, while the other end of the other link is connected to a stationary pivot 15 secured 20 to the upper wall of the channel-like chamber 2. One of the links may be provided with a finger piece 16 for operating the links. In referring to Figures 1 and 4, it will be observed that when the adjustable 25 channel bar 8, which serves as a locking means for holding the index cards in the guideways 3, is in its innermost or locking position, the pivot 14 is beyond or to the left of the line joining stud 11 and pivot 15 30 thus securely holding the bar 8 in locked position. And when it is desired to adjust the bar 8 so that mounted index cards may be inserted or removed, it is necessary to break the toggle by shifting the pivot 14 toward 35 the right into dotted line position, thereby shifting the pivot 11 in the slot and shifting the locking bar 8 into unlocking or dotted line position.

The index cards 17^a are mounted upon 40 supporting and spacing bars 17, the ends of which are adapted to be slidingly retained in the guideways 3. The lowermost card may have its supporting bar rest upon the shelf 5 and other cards may be supported 45 therefrom with their supporting bars resting one upon the other as shown in Figure 8. When a plurality of cards are thuswise supported, it is often desirable to insert a new card at a particular point in the series, 50 or remove one therefrom. In such cases it is desirable to shift the cards upwardly from that point and retain them in such shifted position. Further, it is also often desirable to retain a certain portion of the cards 55 spaced from the others, and to also hold those mounted in the tray in compact form. For accomplishing these objects and purposes, a resilient rod 22 has been provided, the ends of which are adapted to fit in the 60 apertures of the channel bars 6 and 8, and this rod may be applied upon the top of the index cards to hold them in compact form, as shown in Figure 9, or it may be removed by flexing and inserted at any other point. 65 The cards at any point, providing the tray

is not filled, may readily be shifted upwardly and the rod 22 may be inserted to hold them thuswise shifted. The rod 22 is preferably provided with roller-like enlargements 23 adapted to bear against the bars 17 so that the main portion of the rod is sufficiently spaced from the bar it supports so that it can be more readily manipulated, and as many rods 22 as necessary may be used. 70

It should be noted that the outer ends of the rods 22 are always concealed in the channel-like chambers in the tray, and cannot interfere with the use of the tray in a cabinet, and will not be exposed to harm the individuals using the system. 75

In referring to Figures 1 and 2, it will be noted that the rear end of the tray is provided with a pair of anchor holes 24 which are adapted to removably receive hinge members on an anchor 25 slidably supported 80 on the ledges 26 of a cabinet adapted for receiving and housing the trays. In referring to Figure 2, it will be observed that the toggle links of the tray are broken and hence the locking bar 8 is not in locking position. However, further inward movement of the tray will cause the vertical wall of the adjacent ledge of the cabinet to operate the toggle and bar 8 to locking position. It is therefore impossible to place the tray in 85 the cabinet when the cards are in unlocked position, if they should be in unlocked position, they will be automatically locked when the tray is inserted in the cabinet. 90

As the card-supporting bars 17 are freely 95 slideable in the guideways, it is evident that a card mounted upon its support can be inserted at any point or removed therefrom. In doing this, it is however, necessary to operate the toggle and move the locking bar 8 to unlocking position; then by shifting a bar 17 by an endwise movement to the right as viewed in Figures 3 and 9, the left-hand end will become free of the guide flange 4 so that it and the card may be removed from the tray. A reverse operation is required for inserting a mounted card. In such case, the right-hand end of the bar is inserted in its guideway sufficiently far so that the left-hand end will clear the guide flange 4; then by shifting the bar slightly to the left, it will be loosely held by the guide flanges. And by operating the toggle links to bring the bar 8 to locking position, the cards become securely locked against removal. 100

From the foregoing description, it will be apparent that I have provided a novel form of card tray in which cards can be readily inserted and removed at any point, and in which the cards can be locked against removal. 105

I am aware that numerous details of construction may be varied through a wide range without departing from the princ- 110

ples of this invention, and I therefore do not purpose limiting the patent granted otherwise than necessitated by the prior art.

I claim as my invention:

5 1. A card-supporting tray comprising a member having side channels, guideways adjacent said channels, a stationary bar mounted in one channel and an adjustable bar mounted in the other channel, and 10 mechanism connecting said adjustable bar to said member for shifting said adjustable bar to locking or unlocking position.

2. In a card-supporting tray having guideways for slidably receiving cards, a 15 support for the lowermost card comprising a plate member having a flange forming the front end of said tray, and a flange upon which the lowermost card is adapted to be supported.

20 3. A card-supporting tray comprising a metal member having its side margins turned inwardly in overlapping relation so as to form channels and guideways, perforated bars secured in said channels and 25 forming the outer vertical walls of said guideways, one of said bars being transversely adjustable in its channel, and the front wall of said channel having a diagonal slot, a stud projecting from said adjustable bar through said slot, and mechanism connected with said stud for adjusting and locking said adjustable bar.

4. A card index tray having guideways for supporting said cards, and hollow 30 chambers beyond the walls of said guideways for the purpose described.

5. A card index tray comprising a member having inturned flanges forming channels, and guideways, and walls between the 40 channels and guideways for the purpose described.

6. The combination with a cabinet having a tray compartment, of a card-holding tray adapted for insertion in said compartment, a transversely adjustable element in said tray for locking or unlocking said cards with respect to said tray, and mechanism connecting said tray and element and operable when inserting said tray in said 50 compartment for adjusting said element to locking position.

7. A card-supporting tray having lateral overhanging flanges for retaining cards therebeneath, a bar beneath one of said flanges, said last-mentioned flange having an oblique slot, and said bar having a stud projecting through said slot, and operating means connecting said stud and tray.

8. In a card index, a cabinet, a plurality 60 of card supports, a tray therefor, an adjustable bar for engaging the ends of said supports, a shiftable connection between said

bar and tray adapted to be automatically actuated by relative movement of said tray and cabinet.

9. In a card index, a cabinet, a tray slideable in said cabinet, card supports in said tray, an adjustable bar in said tray for engaging the ends of said supports, and movable means associated with said bar engageable with said cabinet by relative movement of said tray and cabinet adapted to shift said bar for locking said sheet supports in said tray.

10. In a card index, a cabinet, a tray slideable in said cabinet, sheet supports in said tray, a transversely adjustable locking bar for engaging the ends of said sheet supports, and means attached to said bar adapted to be automatically actuated by relative movement of said tray and cabinet for shifting said bar to locking position.

11. In a card index, the combination with a cabinet, of a tray slideable in said cabinet, sheet supports in said tray, and means actuated by relative movement of said tray and cabinet for locking said sheet supports against endwise movement.

12. In a card index, the combination with a cabinet, of a tray slideable in said cabinet, sheet supports in said tray, and transversely shiftable means and operating means therefor, adapted to be automatically actuated by relative movement of said tray and cabinet for locking said sheet supports against endwise movement.

13. In a card index, the combination with a cabinet having a tray compartment, of a tray slideable in said compartment, card supports mounted in said tray and means comprising a transversely shiftable locking bar operable by relative movement of said tray and cabinet for locking said card supports against endwise movement.

14. In a card index, the combination with a cabinet, of a tray slideable in said cabinet, card supports in said tray, a transversely adjustable locking bar adjacent one side of said tray, and means engaging said bar adapted by relative movement of said tray and cabinet, for shifting said bar against the adjacent ends of said card supports for locking the same against endwise movement.

15. In a card index, a tray having inturned marginal flanges, card supports retained under said flanges, an adjustable locking bar under one flange, said last-mentioned flange having an oblique slot and said bar having a stud projecting into said slot for the purpose set forth.

In testimony whereof I have hereunto subscribed my name.

GEORGE H. DAWSON.
